(57) **CLAIM**

We claim the ornamental design for a solid particle filter trap, as shown and described.

DESCRIPTION

FIG. 1 is a top perspective view of the solid particle filter trap embodying our design;

FIG. 2 is a bottom, side perspective view thereof;

FIG. 3 is a top plan view thereof;

FIG. 4 is a side view thereof;

FIG. 5 is an end view thereof; and,

FIG. 6 is a bottom plan view thereof.
